UNITED STATES PATENT OFFICE.

CARL J. IPSEN, OF JAMESTOWN, NEW YORK.

CARBURETER.

1,307,975.

Specification of Letters Patent. Patented June 24, 1919.

Application filed September 28, 1917. Serial No. 193,788.

To all whom it may concern:

Be it known that I, CARL J. IPSEN, a citizen of the United States, residing at Jamestown, in the county of Chautauqua and State 5 of New York, have invented new and useful Improvements in Carbureters, of which the following is a specification.

This invention relates to carbureters, the object in view being to provide a carbureter 10 which will handle different grades of hydrocarbon oils such as benzin, gasolene, petroleum, crude oil and others, the carbureter embodying a construction in which the liquid fuel after being drawn into the body of the 15 carbureter is forced to circulate around a ball-shaped chamber which is in direct communication with the explosion or combustion chamber of the engine, the entrance of the fuel to said chamber being controlled by a 20 valve and the entrance of the mixture after circulating around the ball-shaped chamber being controlled by an automatic intake valve which admits the mixture from the chamber surrounding the ball, the ball being 25 interiorly heated by the rapidly recurring explosions within and adjacent to said ball.

With the above and other objects in view, the invention consists in the novel construction, combination and arrangement of parts, 30 herein described, illustrated and claimed.

In the accompanying drawings:—

Figure 1 is a vertical diametrical section through a carbureter embodying the present invention.

Fig. 2 is a top plan view of the same.

Fig. 3 is a horizontal section through the carbureter on the line 3—3 of Fig. 1.

Fig. 4 is a section on the line 4—4 of Fig. 1.

Fig. 5 is a section on the line 5—5 of Fig. 1.

Referring to the drawings 1 designates the main body of the improved carbureter, 2 the fuel and air inlet connection thereof 45 and 3 the outlet connection which leads to the combustion chamber of the engine. The outlet connection 3 is preferably formed as an integral part of the body 1, being cast in one piece therewith and is provided with an 50 attaching flange 4 adapted to receive bolts or other elements 5 by which the carbureter is secured directly to an engine, the end of the connection 3 preferably extending beyond the flange 4 in order that it may be 55 inserted in an opening formed in the head

or other part of the cylinder and communicating with the combustion chamber thereof. The inlet connection 2 is preferably formed separately from the body 1 and is flanged as shown at 6 and secured by suitable fastening means to the body 1. The inlet connection 2 is shown as provided with a lateral air entrance port 7 and is formed at its inner end with a valve seat 8 with which co-operates an automatic inlet valve 9 yieldingly held against its seat by means of a spring 10 which surrounds the stem 11 of the valve, the tension of the spring 10 being regulated by means of a nut 12 threaded on the stem 11.

The inlet connection 2 comprises a plurality of fuel passages 13 and leading to each of said passages is a separate and independent fuel feed pipe, 14 designating for example a feed pipe for a low grade of oil, 15 another feed pipe for a different grade of oil, and 16 a feed pipe for a higher grade of oil such as gasolene or benzin. Each of the feed pipes 14, 15 and 16 is controlled by a regulating valve or cock 17 which enables 80 any one of several grades of fuel to be fed to the carbureter.

Within the main body 1 of the carbureter is a combustion chamber 18 preferably of spherical formation, the same being shown as inclosed by a substantially spherical wall 19 illustrated as formed integrally with the body 1 of the carbureter. The wall 19 is in spaced relation to the body or wall 1 of the carbureter thereby leaving a vaporizing 90 chamber 20. All of the passages 13 intersect the valve seat 8 and therefore when any one of said passages is being used as an oil feed passage, it is automatically uncovered by the inlet valve which is unseated by the suction of the engine and air drawn in through the opening 7 is carried rapidly past the discharge end of said passage 13, taking up the hydrocarbon oil and carrying an explosive mixture into the vaporizing chamber 20.

The mixture as it enters the inward portion of the vaporizing chamber, is sucked or drawn around the wall 19 through an orifice 21 formed through a web or partition 22 which extends at an angle across the upper portion of the chamber 20 and leads the mixture to a valve controlled port or inlet opening 23 in the top of the spherical wall 19. The port or opening 23 is controlled by an automatic intake valve 24 which serves also 110

as the intake valve of the engine, said valve 24 being yieldingly held against its seat by means of a spring 25 surrounding the stem 26 of the valve and adjustable as to its tension by means of a nut 27 threaded on the stem 26. The stem 26 operates through a guide 28 extending upwardly from a head-piece 29 forming the top wall of the chamber 20 and secured thereto by fastening means 10 30. 31 designates a priming cup controlled by a valve 32. 33 designates a spark plug opening which is located in the bore 34 of the outlet connection 3 and between the combustion chamber 18 of the carbureter and 15 the combustion chamber of the engine.

From the foregoing description taken in connection with the accompanying drawings it will now be seen that, due to the suction of the engine, air will be drawn through 20 the connection 2 into the chamber 20 and will take up and carry into the mixing chamber, liquid fuel passing through the passage 13. In starting the engine when cold, gasoline, benzin or other highly volatile hydro- 25 carbon oil may be used, but after the wall 19 of the combustion chamber 18 becomes heated by repeated explosions, the higher grade of fuel oil may be cut off and the lower grade supplied to the carbureter, the latter 30 being adjusted accordingly. The mixture is forced to impinge against the highly heated ball-shaped chamber, first against the lower part thereof then around the upper part thereof by means of the partition or web 22 35 and is finally drawn into the combustion

chamber 18. In the compression stroke of the piston of the engine, the valve 24 is automatically closed and at the proper period an explosion takes place at the plug inserted through the opening 33. Thus the bore 34 40 and the chamber 18 form in effect extensions or parts of the combustion chamber of the engine.

The carbureter has been found effective and reliable in actual use and requires little 45 or no attention as there are no fragile or delicate parts to get out of order and no special adjustment is required. While the carbureter has been designed with special reference to the use thereof in connection 50 with stationary engines, it may of course be used in connection with explosive engines of various kinds.

I claim:—

A carbureter comprising a main body in- 55 closing a mixing chamber, a combustion chamber located within said mixing chamber, an inlet valve controlling the admission of air and fuel to said mixing chamber, an intake valve controlling the admission of 60 said mixture to said combustion chamber, and a mixture deflecting partition extending across said mixing chamber and serving to direct the mixture against, around and over the wall of said combustion chamber 65 before it enters the last named chamber, said partition having an opening through which the mixture is drawn.

In testimony whereof I affix my signature.
CARL J. IPSEN.
